UNITED STATES PATENT OFFICE

2,393,868

HEATING SYSTEM FOR REFRIGERATOR CARS

Charles David Niven, Ottawa, Ontario, Canada,
assignor to The Honorary Advisory Council for
Scientific and Industrial Research, Ottawa,
Ontario, Canada

Application July 9, 1942, Serial No. 450,316

8 Claims. (Cl. 237—5)

This invention relates to improvements in heating systems for refrigerator cars of the type employing fuel heating means connected to coils on the interior of the car through which heating liquid is circulated. The objects of the invention are to provide for more effective control of the temperature of the car through regulation of the circulating liquid and the heating means.

When refrigerator cars are used during cold weather it has been the practice for some time to provide for some form of heating means. In my United States Patent No. 2,076,961, dated April 13, 1937, a convenient form of such heating means has been illustrated. It is desirable, however, that in such a device means should be provided for controlling both the circulation of the heating fluid medium and the combustion of the solid fuel by means of which it is heated.

According to the present invention a thermostatic control is provided applicable to trucks, railway cars and the like, adapted for the transportation of perishable products and equipped with fuel heating means located below the floor of the car. In its construction the invention comprises a double control consisting in the first place of a thermostat located on the interior of the car and designed to control the flow of the liquid in the heating coil whereby a portion or all of the circulating liquid may be caused to flow through a suitable by-pass pipe, and an auxiliary thermostat controlled by the temperature of the liquid in the by-pass pipe and adapted to control the solid fuel heating means, means in the form of a thermal trap or traps being preferably provided to prevent undesirable back circulation of the heating liquid, all as hereinafter more fully set forth and described in the accompanying specification and drawings.

In the drawings:

Figure 1 is a diagrammatic top plan of a portion of a refrigerator car with parts removed showing the heating system installed therein.

Figure 2 is a sectional side elevation showing certain portions of the system.

Figure 3 is a sectional elevation of a thermal trap employed in the system.

Figure 4 is a sectional elevation partly diagrammatic showing the control means operated by the main thermostat.

Figure 5 is a sectional elevation taken on the line 5—5 of Figure 4.

Figure 6 is a detail in elevation showing the link mechanism for operating the draught control from the auxiliary thermostat.

Figure 7 is a perspective detail of one of the contact members of the valve.

Figure 8 is a section on the line 8—8 of Figure 4.

5 In the drawings like characters of reference indicate corresponding parts in all the figures.

Referring to the drawings, A indicates a refrigerator car or truck, which may be of any convenient construction and a portion only of which is shown.

10 B indicates a solid fuel heater, conveniently located beneath the floor 10 of the car and which may be of any convenient design, such as that shown in my aforesaid Patent No. 2,076,961, the combustion in the heater being adapted to be controlled by a suitable damper 11 of any convenient design.

C indicates the heating coil connected in series with the heater and through which heating liquid is circulated, this heating liquid being preferably a suitable antifreeze solution. The pipes C are suitably connected to fluid heating means forming part of the heater B, and the coils C are suitably arranged on the interior of the car 20 to effect the desired heating thereof, the direction of flow of the liquid through the coil C being indicated by arrows. The heater B may be conveniently heated by charcoal contained in the usual firepot in the heater and supplied from a suitable hopper, as set forth in my earlier patent.

25 D indicates the main controlling thermostat, which is situated inside the car, preferably under the floor racks 12. It may be of any convenient design, that illustrated including a large bimetallic coil 13.

The thermostat D is designed to control a valve E, the construction of which is shown in detail in Figures 4, 5, 7 and 8. This valve includes a casing 14, the lower part of which is connected 30 to the riser pipe 15 which should be thermally insulated or lagged and which forms part of the circulating coil system C, and alternative outlet pipes 16 and 17, the pipe 17 forming part of the usual circulating system of the heating coils on the interior of the car, while the pipe 16 constitutes a by-pass for the return of the heating fluid medium when the usual or main circulation is closed as hereinafter described. This by-pass pipe 16 should be thermally insulated to prevent 35 its heating up the car.

The function of the valve E is to direct the heated fluid from the charcoal heater either through the heating coils in the car or through the by-pass pipe. It is desirable that the valve 40 should move with as little power as possible, and

in the embodiment illustrated it is constructed with a pivoted flap member 18 adapted to carry contact members 19 and 20 on opposite sides designed to control the outlet from the casing to the pipes 16 or 17. To facilitate the control, conical reducing members 21 and 22 are provided on the ends of the pipes 16 and 17 having screw threaded or other suitable engagement with the ends of these pipes. The opening ends of these conical reducing pieces may be quite small in 10 diameter, say of the order of half an inch, and they are carefully machined to fit the contact members 19 and 20.

Each of the contact members 19 and 20 includes a triangular plate 23 loosely mounted on transverse posts 24 supported on the plate 18, which is fixed to and turns with the shaft 25, and which is suitably journaled in the casing 14. Springs 26 surround the posts 24 on each side and hold the plates 23 in their outermost position against nuts 27. The plates 23 at the outer side carry contact pieces 28 of brass. By adjusting the nuts 27 the position of the contact plates 23 may be adjusted accurately so as to close exactly over one or other of the conical members 21 and 22.

The plate 18 which constitutes the flap of the valve, is accurately balanced and designed to be moved from the thermostat by suitable link mechanism. In the form of this mechanism illustrated the end of the shaft 25 is provided with a crank 29, the outer end of which has sliding engagement with the end of a lever 30, mounted in a tubular extension 32 supported on the casing 14. The opposite end of the lever 30 is connected through a coupling 31 to the end of the bimetallic coil 13 on the thermostat. The bimetallic coil 13 as it expands or contracts is adapted to move the lever 30 in a direction substantially at right angles to its axis, as indicated by the arrows in Figure 4. To guide this movement and prevent excess movement stops 31a may be provided on the coupling 31 co-operating with corresponding spaced stops 31b provided on a suitable base plate 31c, which may be conveniently connected to the floor of the car.

In order to permit free movement of the arm of the lever 30 and to prevent escape of the heating fluid from the casing 14 the lever is partially enclosed by a flexible tube 33 connected by a threaded adapter 34 to the extension 32 and having at its outer end a connector 35 which is fastened to the lever 30. In this way the increase or reduction in curvature of the bimetallic coil of the thermostat D is caused through the lever 30 and crank 29 to operate the flap plate 18 moving it into alternative positions in which one or other of the pipes 16 or 17 is closed or to some intermediate position in which the outlets to both pipes are open.

In order to prevent the circulation of a random nature inside the pipe when the inlet to the main line is closed a thermal trap F is inserted in the pipe 17 adjacent to the valve E. This trap F, which may be of a form shown in Figure 3, is formed with a baffle member 36 extending from the top of the trap downwardly and designed to prevent the hot liquid from travelling along the top of the pipe and cold liquid returning to take its place along the bottom. It will be observed that the passageway defined between the baffle member and the bottom wall of the trap is of a depth which is a small proportion of the total height of the liquid in the pipe 17.

It is desirable that means should be provided

5 for adjusting the thermostat D from the exterior of the car. The means which I have illustrated for this purpose include a rod 37 connected to pivoted arm 38 on the thermostat and designed to effect slight winding or unwinding of the coil 13, the outer end of the rod having screw threaded engagement with a sleeve 39, the sleeve being rotatively mounted in a suitable support 40, and being designed to be turned in its support by means of a rod 41 having a crank 42 at its outer extremity mounted in a suitable control box 43.

The liquid passing into the by-pass pipe 16 is designed to be returned to the heater B through coils 44 and 44a leading to a connecting T 45 which joins with the return pipe 46 which should be thermally insulated or lagged and which is part of the main circulating system. The main and by-pass pipes thus meet at the T 45, and in order to prevent random circulation adjacent to 15 this point a thermal trap 47 having a similar construction to the trap F as shown in Figure 3 but with the prong or dam extending upwardly is provided in the coil 44 adjacent to the T 45. It will be observed by reference to Figure 2 that 20 the relatively long pipe legs 47a and 47b are provided on opposite sides of the trap 47 so that the fluid is caused to pass upwardly to and through 25 the trap and then downwardly.

G indicates the auxiliary thermostat connected 30 to the by-pass pipe 16 in such a way that it will be affected by the temperature of the liquid passing therethrough, this thermostat being operatively connected to the damper 11. The thermostat G may be of any convenient design, preferably including a bimetallic coil which, when heated by the hot liquid passing through the by-pass, will be moved with sufficient power to operate the draught control 11 and may be protectively surrounded by a metal box. The convenient form of connection is illustrated in which 35 the arm 48 connected to the end of the thermostat passes through and has loose engagement with a lever 49 which is pivoted intermediate of its length to a suitable base plate 50 affixed to the car. The lower end of this lever is connected by a connecting rod 51 with the movable part of the damper 11. The lower end of the lever is adapted to swing between two adjustable stops 52 and 53, the latter stop having arranged at its inner face a pivoted contact piece 54 which may be swung out of engaged position as indicated in dotted lines in Figure 6. This contact piece 54 will normally lie in position over the end of the stop 53 so that movement of the lever will 40 be limited on one side by the stop 52 and on the other side by the contact member 54. When it is desired to cut off the fire completely, however, the contact piece 54 is swung upwardly and the lower end of the lever is moved against the stop 53 as shown in dotted line in Figure 6. The lever may be conveniently held in this position by means of a spring 55 fastened at one end to the plate 50 and designed to be releasably engaged with the upper end of the lever 49. The spring 55 should be strong enough to overcome any tendency of the thermostat to move it due to cooling.

It will thus be seen that when the main thermostat E moves on account of the car being too warm, it closes off the circulation in the main circulating pipe 17. This directs the heated liquid into the by-pass pipe 16, which then heats up, operating the thermostat G moving the damper control 11, which in turn reduces the fire in the heater B. When the car cools the reverse of these operations takes place.

It will be seen from the foregoing that there is an automatic control both of the amount of liquid circulated in the car and of the heating means.

The position of the thermal traps F and 47 has an important effect on the control of the circulating medium. The trap F should be located beyond the riser pipe 15 in the usual circulation of the heating medium and also beyond the valve E which is conveniently placed at the point where the usual circulating pipe emerges from the thermally insulated box around E. It will be found desirable in practice to provide insulation about the valve E and the portion of the pipe 16 inside the car and the portion of the pipe 17 between the valve E and the trap F, the desired condition being that no heat can escape from circulation system into the car when the by-pass operates. The thermal trap 47 is located at the end of the by-pass pipe near where it joins the return of the usual circulation. It will be seen, therefore, that the thermal trap F prevents random hot liquid circulation while the trap 47 prevents random cold liquid circulation.

What I claim as my invention is:

1. A heating system for refrigerator cars comprising in combination circulating coils extending in the interior of the car, heating means located outside the car, a connection adapted to feed a heating medium from the heating means to one end of the coils and a connection adapted to carry the return from the other end of the coils back to the heating means, a by-pass pipe adapted to receive heating medium diverted from the coils and return it to the heating means for recirculation, said by-pass pipe having a portion extending on the exterior of the car by which heat may be dissipated, valve means adapted to be positioned by thermostatic means responsive to the temperature inside the car to close off access of the heating medium either to the by-pass pipe whereby the heating medium is circulated through the coils to return, or to close off access to the coils whereby the heating medium is diverted to the by-pass pipe and returned to the heating means for recirculation.

2. A heating system for refrigerator cars comprising in combination circulating coils extending in the interior of the car, heating means located outside the car, a connection adapted to feed a heating medium from the heating means to one end of the coils and a connection adapted to carry the return from the other end of the coils back to the heating means, a by-pass pipe adapted to receive heating medium diverted from the coils and return it to the heating means for recirculation, said by-pass pipe having a portion extending on the exterior of the car by which heat may be dissipated, valve means adapted to be positioned by thermostatic means responsive to the temperature inside the car to close off access of the heating medium either to the by-pass pipe whereby the heating medium is circulated through the coils to return, or to close off access to the coils whereby the heating medium is diverted to the by-pass pipe and returned to the heating means for recirculation, said valve means comprising a casing having an inlet for the heating medium, an outlet port leading to the circulating coils and an outlet port leading to the by-pass pipe, and a flap valve member swingable by the thermostatic means to close one or other of the ports, the valve member having adjustable spring-supported contact pieces adapted automatically to

engage the ports at the correct angle to completely close the same.

3. A heating system for refrigerator cars comprising in combination circulating coils extending in the interior of the car, heating means located outside the car, a connection adapted to feed a heating medium from the heating means to one end of the coils and a connection adapted to carry the return from the other end of the coils back to the heating means, a by-pass pipe adapted to receive heating medium diverted from the coils and return it to the heating means for recirculation, said by-pass pipe having a portion extending on the exterior of the car by which heat may be dissipated, valve means adapted to be positioned by thermostatic means responsive to the temperature inside the car to close off access of the heating medium either to the by-pass pipe whereby the heating medium is circulated through the coils to return, or to close off access to the coils whereby the heating medium is diverted to the by-pass pipe and returned to the heating means for recirculation, said valve means comprising a casing having an inlet for the heating medium, an outlet port leading to the heating coils, and an outlet port leading to said by-pass pipe, both of said ports having conical reducing members, and a flap valve member swingable by said thermostatic means to close off access to one or other of said ports, said valve member having adjustable spring-supported contact pieces adapted automatically to engage said reducing members at the correct angle to completely close the respective ports.

4. A heating system for refrigerator cars comprising in combination circulating coils extending in the interior of the car, heating means located outside the car, a connection adapted to feed a heating medium from the heating means to one end of the coils and a connection adapted to carry the return from the other end of the coils back to the heating means, a by-pass pipe adapted to receive heating medium diverted from the coils and return it to the heating means for recirculation, said by-pass pipe having a portion extending on the exterior of the car by which heat may be dissipated, thermostatic means responsive to the temperature inside the car adapted to control mechanically the flow of the heating medium by either directing the heating medium to the coils in the interior of the car and thence back to the heating means, or diverting the heating medium from the coils to the by-pass pipe to be returned to the heating means for recirculation, and an auxiliary thermostat responsive to the temperature of heating medium in the by-pass pipe adapted, according to the temperature of such heating medium, to effect control of the combustion of fuel in said heating means.

5. A heating system for refrigerator cars comprising in combination circulating coils extending in the interior of the car, heating means located outside the car, a connection adapted to feed a heating medium from the heating means to one end of the coils and a connection adapted to carry the return from the other end of the coils back to the heating means, a by-pass pipe adapted to receive heating medium diverted from the coils and return it to the heating means for recirculation, said by-pass pipe having a portion extending on the exterior of the car by which heat may be dissipated, thermostatic means responsive to the temperature inside the car adapted to control mechanically the flow of the heating medium by either directing the heating me-

dium to the coils in the interior of the car and thence back to the heating means, or diverting the heating medium from the coils to the by-pass pipe to be returned to the heating means for recirculation, an auxiliary thermostat responsive to the temperature of heating medium in the by-pass pipe adapted, according to the temperature of such heating medium, to effect control of the combustion of fuel in said heating means, a damper for said heating means, link mechanism between the second thermostat and the damper, and regulatable means adapted to limit movement of said link mechanism beyond a predetermined point set to maintain a predetermined minimum opening on which the fire may be kept alive, said means being removable for complete closure of the damper as desired.

6. A heating system for refrigerator cars comprising in combination circulating coils extending in the interior of the car and including an approximately horizontal portion, a heater located outside the car, a connection adapted to feed heating liquid from the heater to one end of the coils and a connection adapted to receive the return from the other end of the coils and carry it back to the heater for recirculation, a by-pass pipe adapted to receive heating liquid diverted from the coils and return it to the heater for recirculation, said by-pass pipe having a portion extending on the exterior of the car by which heat may be dissipated, valve means adapted to be positioned by thermostatic means responsive to temperature inside the car to close off access of the heating liquid either to said by-pass pipe whereby the liquid is circulated through the coils to return, or to close off access to said coils whereby the heating liquid is diverted to the by-pass pipe and returned to the heating means for recirculation, and a thermal trap arranged in the approximately horizontal portion of the coils adjacent to said valve and adapted to prevent the hot liquid from travelling along the top of the pipe and the cold liquid returning along the bottom to take its place.

7. A heating system for refrigerator cars comprising in combination circulating coils extend-

ing in the interior of the car and including an approximately horizontal portion, a heater located outside the car, a connection adapted to feed heating liquid from the heater to one end of the coils and a connection adapted to receive the return from the other end of the coils and carry it back to the heater for recirculation, a by-pass pipe adapted to receive heating liquid diverted from the coils and return it to the heater for recirculation, said by-pass pipe having a portion extending on the exterior of the car by which heat may be dissipated, valve means adapted to be positioned by thermostatic means responsive to temperature inside the car to close off access of the heating liquid either to said by-pass pipe whereby the liquid is circulated through the coils to return, or to close off access to said coils whereby the heating liquid is diverted to the by-pass pipe and returned to the heating means for recirculation, and a thermal trap arranged in the approximately horizontal portion of the coils adjacent to said valve and adapted to prevent the hot liquid from travelling along the top of the pipe and the cold liquid returning along the bottom to take its place, said trap comprising a passageway for the heating liquid and a baffle member extending from one side of the passageway towards the opposite side and defining with such opposite side a restricted passageway of a depth which is a small proportion of the total height of liquid in the immediately adjacent portions of the circulating coils.

8. A heating system as defined in claim 7 in which the by-pass pipe includes an approximately horizontal portion, and a thermal trap in the flow in such portion adapted to prevent hot liquid travelling along the top of the by-pass pipe and cold liquid returning along the bottom to take its place, said trap comprising a passageway for the heating liquid and a baffle member extending from one side of the passageway towards the opposite side and defining with such opposite side a restricted passageway of a depth which is a small proportion of the total height of liquid in the adjacent portions of the by-pass pipe.

CHARLES DAVID NIVEN.
